BOILER

Thomas B. Stillman, South Orange, N. J., assignor to The Babcock & Wilcox Company, Bayonne, N. J., a corporation of New Jersey

Application August 19, 1932, Serial No. 629,463

7 Claims. (Cl. 122—265)

This invention relates to steam boilers of the water tube type, and, more particularly, to water tube boilers, which due to their capacity for high rates of evaporation, lightness and compactness of construction, are especially adapted for marine installations.

One steam boiler construction embodying the above characteristics and which has gone into extensive use is commonly known as the "White-Forster" type. Boilers of this type are further characterized by their capacity for the replacement of any of the tubes in the steam generating bank without disturbing any other tube; this property being attained by bending and positioning each of these tubes so that it is curved longitudinally and laterally and slightly enlarging the tube diameter at the steam and water drum end, allowing the tube to be withdrawn or installed through the drum manhole opening. In such boilers, the tubes in the upper section of the bank are curved longitudinally opposite to the curvature of the tubes in the lower section, thus leaving a space between the adjacent rows of tubes in the two sections. In attempting to adapt a boiler of this type to modern steam generating conditions, involving the production of highly superheated steam, this space has been utilized as the location of a steam superheater. It has been found in practice that the amount of superheating surface capable of being incorporated in that location is extremely limited and cannot be increased without disadvantageously affecting the structural characteristics of the boiler. This superheater location is further disadvantageous because the temperature of the heating gases is substantially reduced before it reaches the superheater. The small amount of superheating surface present and the reduced heating gas temperature at that point jointly limit the degree of superheating obtainable to a value below that required for the operation of modern steam utilizing devices at high efficiencies.

The general object of my invention is the provision of an improved construction of a steam boiler of the water tube type.

A further and more specific object is the provision of a high capacity express type marine boiler having an improved construction and arrangement of steam superheating surface.

Another specific object is an improved proportioning and arrangement of steam generating, superheating, and feed water heating surface in a boiler of the character described.

Another specific object is the provision of supporting means for a multiple tube bank steam

boiler permitting substantially free expansion and contraction of the tubes connecting the drums.

Another specific object is the provision of an improved location and construction of an economizer in a boiler of the character described.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings—

Fig. 1 is a sectional elevation of a boiler of the White-Forster type, modified in accordance with my invention;

Fig. 2 is a section on the line 2—2 of Fig. 1;

Fig. 3 is a fragmentary view illustrating a modified economizer construction;

Fig. 4 is a detail partly in section illustrating the connection of the economizer tubes to one of the headers; and

Fig. 5 is a front view of the structure shown in Fig. 4.

In the steam boiler illustrated in the drawings, the reference numeral 1 designates a horizontal steam and water drum of large diameter extending along and above one wall of the boiler setting 14. Below and laterally spaced from the drum 1 is a water drum 3 connected thereto by a bank of steam generating tubes 2. Each of the tubes 2 is curved in two directions, as indicated in Figs. 1 and 2 to permit its replacement through the manhole opening 1^a at one end of the drum 1 without interfering with any other tube in the bank. The bank of tubes 2 is divided into upper and lower sections 2^a and 2^b, respectively, the tubes in the two sections being oppositely curved in one direction, leaving a narrow space between their adjacent rows.

The space available between the sections of the tube bank has been found inadequate for the location of the amount of superheating surface required for the desired degree of superheat with heating gas temperatures as at that point. The required degree of superheat is attained in the present construction by the location of the desired amount of superheating surface between the bank of tubes 2 and the combustion chamber 15. The superheater is preferably formed by a pair of curved headers 11 and 12 superposed in an

offset chamber 13 formed in one of the side walls of the boiler and connected by nested rows of U-tubes 10 extending across the boiler with their return bend portions positioned in a similarly offset chamber 13^a at the other side of the boiler. The chambers 13 and 13^a, and headers 11 and 12, extend parallel and adjacent to the lowermost row of tubes 2. In the superheater construction shown, the header 11 is divided at an intermediate point by a transverse partition 11^a into inlet and outlet chambers having steam inlet and outlet connections 11^b and 11^c, respectively, connected thereto. A conduit 55 connects the header inlet chamber to the steam and water drum 1, while the outlet connection 11^c leads to any steam utilizing device. The superheater tubes are expanded into the headers 11 and 12 in clusters, and suitable handhole openings and closure devices are provided for allowing access to each tube cluster. The portion of the wall of the chamber 13^a opposite the return bend portions of the tubes is made removable to permit any of the superheater tubes to be replaced through the side of the boiler, rendering unnecessary the provision of space in the fire room sufficient for the withdrawal of the superheater as a unit.

Heat is supplied to the boiler by means of suitable fuel burners positioned in openings 40, located in the boiler front wall below the drum 1. High temperatures are normally maintained in the combustion chamber 15, and to avoid flame impingement on the superheater tubes, a relatively shallow bank of water tubes 6 is arranged between the superheater and the combustion chamber. The tubes 6 are arranged parallel to the superheater headers and connected at their upper and lower ends, respectively, into horizontal drums 5 and 7. The drum 5 extends below and slightly in front of the drum 1, and has a supporting connection therefrom through a row of nipples 4. The drum 7 is positioned directly below the drum 3 and connected thereby by nipples 8.

In operation, the tubes 2 and 6 tend to expand and contract in accordance with temperature variations. To permit expansion and contraction of the tubes without damage to the boiler structure, the drum 1 is supported on posts 30, carrying at their upper ends a saddle 31. The drum 7 is likewise supported on saddles 35, and through the nipples 8 supports the drum 3 thereabove. With this arrangement of the parts, each tube bank is fixed at a different end and substantially free to expand and contract to or from the other end. The nipples 4 and 8 permit some lateral movement of each of the supported drums relative to the adjacent supporting drum. Some compensation for expansion and contraction is also attained by the curvature of the steam generating tubes.

An effective heat transfer is established in the boiler by proportioning the tube diameters and spacing to provide a successively increasing amount of heating surface in the pass through which the heating gases flow, and by progressively decreasing the effective gas flow areas to correspondingly increase the mass flow of heating gases per unit of heat transfer area. As shown in Figs. 1 and 2, the first two rows of tubes 6 are of relatively large diameter, whereas the remaining rows in that bank contain a larger number of tubes of smaller diameter. The diameter of the superheater tubes 10 is slightly less than that of the remaining tubes in the bank 6, while the tubes 2 are more closely spaced than the tubes 6

and of less diameter than the superheater tubes.

The heating gases generated in the combustion chamber 15 successively contact with the bank of tubes 6, the superheater, and the main bank of tubes 2, all being compactly arranged in a single gas pass. An economizer is advantageously incorporated in the boiler construction described, and as shown in Figs. 1 and 2, the economizer consists of superposed horizontal headers 42, 43, 44 and 45 arranged along one side wall of the boiler and serially connecting two superposed groups of U-tubes 46. The economizer is preferably positioned in an obliquely extending portion of the gas pass between the tube bank 2 and gas exit 47 and formed by an inclined baffle 48 and a similarly inclined portion 50 of the boiler setting. The baffle 48 extends from the boiler outlet down to the uppermost row of tubes 2, and the space between its lower end and the adjacent portion of the drum 1 is closed by a complementary baffle 51. The tubes 46 are preferably inclined to the vertical to the same extent as the baffle 48. The flow of heating gases to all portions of the economizer is facilitated by an inclined distribution baffle 52 mounted on the uppermost row of tubes 2 and extending upwardly midway of the gas pass between adjacent economizer tubes.

A relatively large amount of economizer surface can be incorporated in the available space, which is usually of a height substantially the same as the diameter of the drum 1, by swaging down the ends of the economizer tubes, as shown in Fig. 4. The bodies of the tubes can therefore be closely spaced providing high heating gas velocities and high heat transfer rates. The swaged ends of the tubes are expanded in a counterbored tube seat and the belled tube end welded around its entire circumference to the header, as indicated at 53. Hand holes 54 provide visibility for the expanding and welding operations.

The intermediate headers 43 and 44 are connected at one end to provide a serial flow through the economizer sections. Wall baffles 56 prevent short circuiting of the economizer surface, as shown in Fig. 2. The spaces between the headers are closed in any suitable manner.

In operation, the feed water is supplied to the economizer header 42 and flows serially through the economizer sections to the bottom header 45, which is connected to the steam and water drum 1 by a suitable connection 18 opening to the drum 1 below the normal water level therein. The fluid flow is upward in the lowermost tubes of the main tube bank and also in the bank of tubes 6, and downward in the other tubes of the main bank. The steam generated passes from the drum 1 through a pipe 55 to the inlet chamber of the superheater.

The location of the fuel burners in the front wall of the boiler rather than in one of the side walls, reduces the amount of combustion chamber volume and overall boiler height required. In this location, the boiler gauge glass 60 will be directly in view of the operator in charge of the fuel burners. The specified proportioning of the heating surface over which the heating gases pass, provides equi-spaced paths for the heating gases, so that the heat input into the tubes is more nearly uniform throughout their length. The generating capacity of the boiler will be quite high and its compactness and low weight make the design particularly desirable for marine installations.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A water tube boiler comprising a combustion chamber, a horizontal steam and water drum of large diameter, a horizontal water drum spaced therefrom, an inclined bank of curved steam generating tubes connecting said drums, said tubes being curved in two directions, a second inclined bank of curved steam generating tubes in front of and spaced from said first bank, horizontal water drums connected to opposite ends of said second bank, a superheater positioned in the space between said tube banks, nipples connecting the drums at corresponding ends of said banks, and an economizer including return bend tubes extending transversely of and above said first bank, the tubes of said superheater being of less diameter and more closely spaced than the tubes of said second bank, and the tubes of said first bank being of less diameter and more closely spaced than the tubes of said superheater.

2. A water tube boiler comprising a combustion chamber, a horizontal steam and water drum, a horizontal water drum spaced therefrom, an inclined bank of curved steam generating tubes connecting said drums, a second inclined bank of curved steam generating tubes in front of and spaced from said first bank, horizontal water drums connected to opposite ends of said second bank, a superheater positioned in the space between said tube banks, nipples connecting the drums at corresponding ends of said banks, and an economizer including return bend tubes extending transversely of and above said first bank, the tubes of said superheater being of less diameter and more closely spaced than the tubes of said second bank, and the tubes of said first bank being of less diameter and more closely spaced than the tubes of said superheater.

3. A water tube boiler comprising a combustion chamber, a horizontal steam and water drum, a horizontal water drum spaced therefrom, an inclined bank of curved steam generating tubes connecting said drums, a second inclined bank of curved steam generating tubes in front of and spaced from said first bank, horizontal water drums connected to opposite ends of said second bank, a superheater positioned in the space between said tube banks, means for supporting said steam and water drum of said first bank, means for supporting the water drum at the lower end

of said second bank, and means for supporting the remaining water drum of each bank from the supported drum at the corresponding end of the other bank.

4. A water tube boiler comprising a combustion chamber, a horizontal steam and water drum, a horizontal water drum spaced therefrom, an inclined bank of steam generating tubes connecting said drums, a second inclined bank of steam generating tubes below and spaced from said first bank, horizontal water drums connected to opposite ends of said second bank, means for supporting said steam and water drum of said first bank, means for supporting the water drum at the lower end of said second bank, and means for supporting the remaining drum of each bank from the supported drum at the corresponding end of the other bank.

5. A water tube boiler comprising a combustion chamber, a steam and water drum, a water drum spaced therefrom, a bank of steam generating tubes connecting said drums, a second bank of steam generating tubes below and spaced from said first bank, water drums connected to opposite ends of said second bank, means for supporting one of said drums of said first bank, means for supporting the drum at the opposite end of said second bank, and means for supporting the remaining drum of each bank from the supported drum at the corresponding end of the other bank.

6. A water tube boiler comprising a combustion chamber, a horizontal steam and water drum of large diameter, a man-hole formed in one end of said drum, a horizontal water drum spaced therefrom, an inclined bank of curved steam generating tubes connecting said drums, said tubes being curved in two directions to permit their replacement through the man-hole of said steam and water drum, a second inclined bank of steam generating tubes in front of and spaced from said first bank, horizontal water drums connected to opposite ends of said second bank, and a superheater positioned in the space between said tube banks.

7. A water tube boiler comprising a combustion chamber, a horizontal steam and water drum of large diameter, a man-hole formed in one end of said drum, a horizontal water drum spaced therefrom, an inclined bank of curved steam generating tubes connecting said drums, said tubes being curved in two directions to permit their replacement through the man-hole of said steam and water drum, a second inclined bank of curved steam generating tubes in front of and spaced from said first bank, horizontal water drums connected to opposite ends of said second bank, a bank of superheater tubes positioned in the space between said tube banks, and nipples connecting the drums at corresponding ends of said tube banks.

THOMAS B. STILLMAN. 60
